UNITED STATES PATENT OFFICE.

MICHAEL A. DREES, OF PESHTIGO, WISCONSIN, ASSIGNOR OF ONE-HALF TO JAMES I. SCOTT, OF MARINETTE, WISCONSIN.

FOLDING TABLE.

No. 923,500.

Specification of Letters Patent.

Patented June 1, 1909.

Application filed May 5, 1908. Serial No. 430,892.

To all whom it may concern:

Be it known that I, MICHAEL A. DREES, a citizen of the United States, and resident of Peshtigo, in the county of Marinette and 5 State of Wisconsin, have invented a new and Improved Folding Table, of which the following is a full, clear, and exact description.

My invention relates to that type of table, wherein the legs or supports therefor are 10 folded inwardly upon the folding of the table, and it has particular reference to a table wherein the legs or supports are linked together in such a manner that the operation of folding automatically brings the supports 15 into a compact position, embraced by the leaves of the table, and an object of my invention is to provide means whereby tables of the character referred to may be folded with greater facility than by those in vogue 20 and previous to my invention in so far as I am at present aware.

Another object of my invention is to provide a construction of folding tables conducive to durability with regard to the working parts as well as to the entire structure, 25 and to provide a table in compact form which may be marketed at a popular price.

The features of my invention whereby I 30 attain these objects, are illustrated in the accompanying drawings forming part of this specification and pointed out in the claims.

Referring to the drawings, Figure 1 is a bottom perspective view of my improved folding table; Fig. 2 is a perspective view of the table 35 when folded and the two leaves closed down upon each other; Fig. 3 is a longitudinal section of the same showing more clearly certain of the working parts; Fig. 4 is a somewhat enlarged longitudinal section of my improved table when folded, and Fig. 5 is an 40 enlarged sectional detail view hereinafter more fully described.

Similar characters of reference indicate like parts in all the views.

45 A and A¹ indicate two leaves which together form the surface of the table, and B, B¹, B² and B³, B⁴ and B⁵ are the legs thereof. Each of the sections or leaves A and A¹ is provided with a similar framing. The leaf A

has a framing comprising a strip a on one of its sides and at one edge thereof, and a strip a² oppositely situated thereto on the same side, and at the opposite edge thereof. The oppositely situated side strips a¹ and a³. These together with the legs and leaves A and A¹ I prefer to construct of wood and secure the parts referred to together in the manner of framing, and firmly secure the latter to the leaf A by doweling and glue or any other suitable means. The frame of the leaf A' is similarly formed of the members or strips a⁴, a⁵, a⁶ and a⁷. The legs B and B³ carried by the leaf or section A are tied laterally to each other by an upper sliding cross member D² to which they are pivoted, 60 through studs G (see Fig. 5), and rigidly by a lower brace b, and the legs B' and B⁴ situated at the junction of the sections or leaves A and A' are held rigidly by a brace b' and are secured at their upper extremities to the strip a⁷, the strips a³ and a⁷ being pivotally united by hinges F and F', and the legs B' and B⁴ being pivotally secured to the strip a⁷ by hinges F² and F³. The legs B² and B⁵ which are braced by the cross member b² 65 near their lower extremities and are tied adjacent to the section A' of the table, by a sliding cross member D³, and in rotative relation therewith.

The section A has secured to its under surface a stop block D and the section A' has a similar stop block D', and to each of these stop blocks are secured guide clips d and d' which embrace the sliding members D² and D³ respectively, and restrain them from turning. Toward the terminals of the sliding member D² and secured thereto are lugs e and e' which are constructed preferably of steel or other suitable metal and are secured by screws or other effective fastenings. To 80 these lugs are pivoted at corresponding extremities the operating levers C⁴ and C⁵. I prefer to construct these of mild steel, although in some instances where finish is a desideratum, I employ any other suitable 85 material. The remaining terminals of these arms or operating levers are situated oppositely with respect to each other, and are

swung upon studs e^3 respectively driven into the woodwork of the legs referred to or otherwise fastened in any suitable manner.

Connected to the sliding member D^2 of the legs B^2 and B^5 , and similarly to the connection of the braces C^4 and C^5 with the sliding member D^2 , are the operating levers C^6 and C^7 , which at their inner terminals are pivoted to the legs B^1 and B^4 , in common with the corresponding terminals of the operating levers C^4 and C^5 , and to the sliding member D^3 , at e^4 and e^5 .

To the legs B and B^3 are pivotally connected the terminals of the braces C and C^4 respectively, and the opposite terminals thereof are pivotally connected to the end framing a^1 of the section A . The pivotal connections with said legs are effected by the hinges d^3 and d^4 secured respectively to each leg and connecting brace, and the pivotal connection of the braces with the end frame a^1 is effected through the hinges d^2 and d^5 respectively, which are securely fastened to this member. These braces are duplicated at the opposite extremity of the table, where they are carried in pivotal connection with their respective legs B^2 and B^5 , and are designated respectively as C^3 and C^2 and the pivotal or hinge connection with the framing a^5 as d^8 and d^6 .

Each of the terminal legs B and B^3 and B^2 and B^5 are provided with bearing studs G (see Fig. 5), which have at one terminal a bearing head G^1 . These studs pass through perforations in their respective legs, in which perforations they bear in pivotal relation and are driven tightly into the terminals of the respective sliding members D^2 and D^3 . The heads G^1 of these studs during the operation 35 of the table, play in longitudinal grooves or slots as indicated at g^5 , in their respective side bars a , a^2 , a^4 and a^6 , and toward the outer terminals thereof and adjacent to the 40 under surface of the two sections A and A^1 of the table, while the sliding members D^2 and D^3 carrying the terminal legs of the table, to which they are swung by the studs G , play to and fro under the guide clips d^1 and d^3 respectively.

The operation of my improved table, assuming the same to be in an open position as illustrated in Figs. 1 and 2, is effected by turning the table top down upon the floor 45 with the legs uppermost, or upon its side and folding the two sections A and A^1 toward each other. To facilitate the description of the operation, let it be assumed that the table is turned with its face down and the 50 folding is proceeded with by swinging the section A^1 toward the section A ; the effect will be when the section A^1 is swung upon the hinges F and F^1 , to slidably force the upper terminals of the legs B^2 and B^5 together with

the sliding member D^3 to which they are pivoted, against the thrust of the braces C^6 and C^7 , and the counter thrust of the pivoted braces C^2 and C^3 to take a position toward the end frame a^2 , while at the same time the opposite extremities of the legs B^2 and B^5 will be swung in a reverse direction, until the section A^1 assumes a position at right angles to the section A , whereupon the legs B^2 and B^5 will be folded within the confines of the side bars a^4 and a^6 , until further movement of these legs is arrested by impinging against the under side of the surface of the section A^1 and against the outer surface at the terminals of the legs B^1 and B^4 , whereupon the motion being continued and the folding proceeded with, the legs B^1 and B^4 will force the arms C^4 and C^5 to similarly throw the terminals of the legs B and B^3 toward the framing A^1 , until these legs will be thrown in a similar manner to that of the legs B^2 and B^5 , into a position within the confines of the side bars a and a^2 , and the table will assume the form illustrated in Figs. 2 and 4, and in appearance resemble a shallow box.

The construction which I have above described is a durable one. It is also inexpensive and affords great facility in operation.

Having thus described my invention, I claim as new and desire to secure by Letters Patent:

1. A folding table comprising a plurality of sections hinged together, said table being provided on its under surface with strips extending around the same and forming a framing, a sliding member arranged transversely of the table at each end thereof, pairs of legs pivoted to the ends of each sliding member, each pivot having a head on its outer end, and the strips being provided with grooves in which the heads move, a brace pivoted to each leg below its pivot on the sliding member, and to the adjacent end of the table, a pair of legs hinged at the junction of the sections, stop blocks secured to the under surface of the table in position for engagement by the sliding members, when the table is in erect position, and levers each having one end connected with the respective end of a sliding member, and its other end pivoted to the central pair of legs.

2. A table comprising a plurality of sections hinged together, a pair of legs at the junction of the sections and hinged to said table sections, a pair of legs at each end of the table, sliding members movable on the under face of each section, stop blocks on the under surface of each section for engagement by the sliding members when the table is in erect position, and operating levers connecting the ends of the sliding members with the adjacent member of the central pair of legs, bearing studs pivotally connecting each pair of

end legs with the adjacent sliding member, said studs having bearing heads, and said table sections having grooves in which the heads move for the purpose set forth.

5 3. A folding table comprising hinged sections, leg supports carried by the sections at their outer ends and slideable longitudinally of the table, legs pivoted to the sliding supports, legs carried in common by the sections
10 at their junction, levers pivotally connecting

the latter legs and the sliding supports, and braces pivoted to the sections at their outer ends and to the adjacent legs.

In testimony whereof I have signed my name to this specification in the presence of 15 two subscribing witnesses.

MICHAEL A. DREES.
